UNITED STATES PATENT OFFICE

DERMONT H. ROBERTS, OF LONG BEACH, CALIFORNIA

IDENTIFICATION DEVICE

Application filed March 16, 1931. Serial No. 523,148.

This invention has relation to a device for personal identification. More particularly my object is to provide, within a small and convenient casing, such instrumentalities as are required properly to identify persons. To this end, my invention resides in the combination hereinafter fully described and illustrated in the appended drawings of which:

Fig. 1 is a side elevation partly in section 10 of a structure embodying the invention,

Fig. 2 is a front elevation of the structure with parts broken away for the sake of clearness,

Fig. 3 is a rear elevation of the device with 15 parts of the casing broken away in order to expose the interior mechanism, and

Fig. 4 illustrates part of the heat element of the structure.

Finger print identification is becoming 20 the accepted means of identification, not only for the purpose of criminal records, but also in hospitals for the purpose of identifying new born babies, in banks for the identification of signatures, and in fact in every 25 line of business. My invention is based upon the finger print principle. For the purpose of making finger prints, it is customary to employ an ink pad against which the person to be identified is directed to place his 30 hand or finger, whereupon he is required to press the hand or finger against a piece of paper upon which part of the ink picked up is deposited.

For the purpose of criminal records such 35 procedure may be acceptable, but in civil life it is objectionable to leave a deposit of ink on the skin after the imprint has been made. In the device of my invention, which I am now about to describe, an invisible printing 40 fluid is employed, the remainder of which quickly evaporates after the imprint has been made leaving no discoloration of the skin and no disagreeable odor. After imprinting, it is necessary to develop the print and means 45 for effecting such development forms part of the present invention. While the police require impressions of all fingers, the thumbs and palm of the hands, it is generally only necessary to obtain the imprint of a certain 50 finger for commercial identification. In view

of this I shall hereinafter, for the sake of simplicity, merely refer to the finger, or a finger.

The device of my invention comprises three main divisions: A grooved table, 1, in front, 55 a central moistening aperture, 2, and a heating device, 3, in the rear.

The operation of my invention is very simple. A check or other instrument in connection with which finger print identification is desired is placed on the table 1. The person, whose finger print is required, is requested to run his finger over a grooved roller 3 of the moistening mechanism and then to 60 press his finger against the surface of the instrument thereby to leave an invisible imprint on the instrument. The operator then places the instrument within the developing mechanism 3, whereupon, in a few seconds, 65 the imprint appears clearly on the face of the 70 instrument.

The construction of the device will now be described in detail. The table 1 is provided with a longitudinal groove 4, as best 75 shown in Figure 2. When making the imprint, the person is requested to place his finger directly above this groove and to press the paper into the groove. This is done, not only to obtain an imprint of the face of the finger, but also of the sides, thereby obtaining 80 imprints of the two deltas of the finger, which have been found to be two of the most important features of identification. In order to secure such imprint on a flat surface, it is necessary to roll the finger on the paper, 85 but this is undesirable because a clear imprint cannot satisfactorily be obtained in such a manner by the layman, and is very 90 awkward.

The moistening mechanism comprises the 95 aforesaid grooved roller 3, which is hung to rotate on a shaft 5, of a fluid reservoir 6, by means of a pair of flanges 7, rising from the sides of said reservoir to support the shaft 5. In the reservoir is set a wick 8, extending from the bottom to the periphery of the roller 3 and curved to fit the shape of the groove 10 of this roller. When the roller is twirled by the thumb to absorb some 100 of the moistening liquid, a small quantity

of this liquid is deposited on the roller by means of this wick. A second wick 9 may be employed in order to absorb a sufficient quantity of liquid. These wicks are made from fine sponge rubber and, when first placed in the reservoir, have been previously immersed in liquid of the same kind and caused completely to absorb such liquid.

It is to be noted, that the aperture in the 10 top of the reservoir, through which the wicks project, must fit very tightly around the wicks in order to prevent leakage of the liquid.

In the top of the reservoir, is drilled a very 15 small hole 11, and the reservoir is provided with a small dome shaped cap 12, covering this aperture. From the top of this dome extends a small tube 13 downwardly along the side of the reservoir. This may be termed 20 a breather tube, and it functions to adjust the air supply within the reservoir to the level of the liquid, that is, as liquid is drawn out of the reservoir, air is permitted to enter through the tube and, when due to a rise 25 in temperature, the liquid expands within the reservoir, air is free to escape through the tube, thereby preventing waste of liquid through the wicks 8 and 9.

In handling a small structure of this 30 character, it is often turned on its side, or turned upside down, and it is important that no liquid shall escape from the reservoir when handled in such manner. The breather tube acts as an air seal when the device is inverted 35 and for this reason, effectively prevents leakage of the liquid. What little liquid may find its way into the cap 12, is free to return into the reservoir when the structure is again set on its feet.

40 It is important that only a very thin film of liquid be deposited on the groove of the roller 3. I have experimented with wicks of every known material and have found that fine sponge rubber is best adapted for 45 this purpose. Under certain conditions, I have, moreover, found it desirable to add a third element, in the shape of a scraper 14, made out of soft rubber and placed behind the wick 8.

50 Such scraper effectively aids in distributing the liquid evenly over the surface of the roller. The reservoir 6 is fastened on a plate 15, and this plate is, by rivets 16, permanently seated in the casing of the device completely 55 to enclose the reservoir and roller. This is necessary in order to prevent anyone from tampering with the device. In order to remove the reservoir and roller, this plate 15 must be broken away, giving clear evidence 60 that it has been tampered with.

65 After an imprint has been made on the surface of the document to be identified, this document is inserted within the groove 20 of the developing mechanism 3. A pair of heating elements, 21 and 22 are placed with-

in a fire resisting support, comprising two members 23 and 24, and these members are permanently combined by means of a pair of bolts 25. The members 23 and 24 are made from porcelain or other suitable fire and heat 70 resisting material, and they are provided with vertically directed grooves, 26, as best shown in Fig. 4. Within there are seated the above named heating elements 21 and 22, comprising rectangular frames 27, around 75 each of which a suitable heating coil, or filament 28 is wound.

The electrical connections to these heating elements are diagrammatically shown to include a switch 29 and a battery 30. In actual practice they are, of course, connected to plug into a socket of the house current. The support for the heating elements is shown mounted on a plate 32, by means of a pair of bolts 31, and the plate in turn is shown fastened to the casing of the structure by means of screws 33. This construction permits of removal of the heating elements for the purpose of repairs. It is important that a certain uniform degree of heat is maintained 80 within the developing mechanism in order to develop the imprints. If insufficiently heated, no development will take place; if overheated, the document will be scorched and its utility destroyed. While the heating 85 elements may be designed to maintain a certain degree of heat, while the current passing through the elements remains uniform, it is necessary to provide for variations due to fluctuations in this current, and this I 90 accomplish by permitting a current of air to pass up through the developing mechanism, not only in the space between the heat elements, but also through a space I provide 95 between the support for the heat elements 100 and the outer casing of the device. In order to make this ventilation more effective, the plate 32 should be provided with a number of apertures 35. It is important to note that, 105 because of this ventilation, the casing does not become heated, it is always comfortable 110 to handle, and the temperature in the liquid reservoir is not affected.

Where imprint of the whole hand, or bottom of the foot is required it is, of course, necessary to use a straight roller and flat table. In such case a larger machine must be employed. But for commercial identification the device, as hereinbefore described, is sufficient.

I claim:

1. In a device for personal identification, a roller, a fluid reservoir, means for transferring fluid from the reservoir to the said roller, an imprint table, and means for developing the imprint made on said table.

2. In a device for personal identification, a grooved roller, means for depositing a film of invisible printing fluid on the groove of said roller, a grooved imprint table, and

means for developing the imprint on a paper placed on said table.

3. In a device for personal identification, a roller, a reservoir, wicks for carrying fluid from the reservoir to the surface of the roller, said reservoir being provided with a breath-
er tube to prevent overflow, a table for a document to be imprinted, and means for developing the imprinted document.
- 10 4. In a device for personal identification, a grooved roller, means for carrying fluid to and distributing the fluid over the grooved surface of the roller, a grooved table to receive a document to be imprinted, and means for developing the imprinted document.

5. In a device for personal identification, a roller, a fluid reservoir, provided on top with a fine aperture and having a fine tube extending from said aperture downwardly
20 along the side of the reservoir, means for raising fluid from the reservoir to the surface of said roller, a table on which to place an instrument to be imprinted, and means for developing the imprinted paper.

25 6. In a device for personal identification, a roller, a fluid reservoir, means in said reservoir for feeding fluid to said roller, a table for receiving a paper to be imprinted, and a heating device within which to place the im-
30 printed paper for the purpose of developing the imprint.

35 7. In a device for personal identification, a roller, means for feeding an invisible printing fluid to said roller, a table for receiving a paper to be imprinted, a heating device in which to insert the imprinted paper for the purpose of developing the invisible imprint, and means for ventilating said heating device in order to prevent scorching of the paper
40 and heating of the casing.

45 8. In a device for personal identification, a casing, a printing fluid reservoir sealed within said casing, a roller hung on said reservoir and seated in an aperture of the casing, and means for feeding fluid from said reservoir to the said roller.

50 9. In a device for personal identification, a casing, a printing fluid reservoir within the casing, a roller rotatably hung on the reservoir and seated in an aperture of the casing, and means for distributing a thin film of fluid from the reservoir on the surface of the roller as the latter is rotated.

55 10. In a device for personal identification, a casing forming a reservoir for a printing fluid, a roller seated in an aperture of the casing for rotation by human fingers, and means for distributing a thin even film of fluid from the reservoir over the surface of
60 the roller when thus rotated.

65 11. In a device for personal identification, a roller, a fluid reservoir, means for distributing a thin film of fluid from the reservoir over the surface of the roller, and an imprint table in front of the roller and shaped to con-

form to the contour of the finger or fingers rotating the roller.

12. In a device for personal identification, a reservoir for a fingerprint fluid, a roller hung on said reservoir, means for distributing a thin even film of the fluid over the surface of the roller as the roller is rotated by a finger or fingers, and an imprint table shaped to conform to the contour of the imprinting finger or fingers.

In testimony whereof I have hereunto affixed my signature.
